WEB THREADER FOR WINDER MACHINES

Charles M. Pearson, Watertown, N. Y., assignor
to The Bagley & Sewall Company, Watertown,
N. Y., a corporation of New York

Application September 15, 1949, Serial No. 115,939

5 Claims. (Cl. 271—2.1)

1

This invention relates to a web threading device for drum winders commonly employed to wind the web of paper coming off from a paper making machine into rolls. The web is trained about a portion of the periphery of a relatively large drum. The leading end of the web is attached to a roll riding freely on the drum. That is, the roll being wound is supported on the drum or, in some instances, it is supported on two drums journaled in close relationship.

The invention has as an object a threading device which functions to thread the leading portion of the web about the supporting drum, especially where the web is fed about the under side or portion of the drum and then upwardly to the winding roll, the device embodying a simple and rugged construction which normally does not engage the paper web or the drum and which is movable into engagement with the paper web to effectively direct it about the drum and upwardly to the winding roll.

The invention consists in the novel features and in the combinations and constructions hereinafter set forth and claimed.

In describing this invention, reference is had to the accompanying drawings in which like characters designate corresponding parts in all the views.

Figure 1 is an end elevational view of a web threading device embodying my invention with the supporting drums and winding roll being shown in dotted outline.

Figure 2 is a side elevational view of the structure shown in Figure 1.

Figure 3 is a sectional view on line 3—3, Figure 2.

Figure 4 is a sectional view on line 4—4, Figure 2.

The device consists of a suitable frame arranged in juxtaposition to and below the winding drum. A pair of rollers are journaled in the frame. An endless belt is trained over these rollers. The rollers extend parallel to the drum and are movable toward and from the drum to bring the upper run of the belt into engagement with the lower portion of the periphery of the drum, whereby the belt is driven by such engagement and is effective to draw the free end of the web between the belt and the under side of the drum. The rollers and the belt extend an appreciable distance lengthwise of the winding drum, and the frame carries means to direct a blast of air against the free end of the web as it leaves the threading belt to maintain it against the periphery of the drum as the web is carried upwardly to the winding roll.

The frame consists of a base member 10 having pedestals 11 mounted on each end thereof and extending upwardly therefrom. The upper ends of the pedestals 11 are apertured to form bear-

2

ings in which spindles 13 are journaled. The spindles 13 constitute extensions from a roll 14. A pair of arms 15 having bosses 16 journaled on the spindles 13 extend forwardly under the winder drum 17, and have journaled between their outer ends, a roll 18. The arms 15 are connected by a tie rod 19 to which is connected a piston rod 20 extending from a cylinder 21, the lower end of which is pivotally mounted upon the base 10.

10 A belt is trained over the rollers 14, 18, the belt being of sufficient length to run slack. A supporting plate 22 is mounted between the arms 15 and is formed with downwardly curved edges 23.

15 The plate 22 serves as a support to maintain the lower run 24 of the belt straight or tangential to the rolls 14, 18. This permits the slack to form in the upper run 25 of the belt.

Normally the arms 15 and the structure carried thereby are positioned so that the upper slack run of the belt 25 is spaced downwardly from the periphery of the winder drum 17, as shown in Figure 3. When it is desired to thread a web 26 about the winder drum 17, fluid is supplied to the bottom of the cylinder 21, whereby

20 the piston rod 20 moves the arms 15 about the spindle 13, elevating the roll 18 to the dotted line position 27, Figure 1, and bringing the upper slack run 25 of the belt into engagement with the drum 17. This engagement causes the belt to be driven about the rolls 14—18. The end of the web 26 is then fed between the belt and the drum.

25 A conduit in the form of pipe 28 is arranged between the pedestals 11 and in proximity to the discharge end of the belt or roll 14. The pipe 28 is formed with a plurality of apertures 30 arranged to direct a blast or sheet of air against the leading end of the web as it leaves the belt and causes it to adhere to the periphery of the drum 17 as it passes from between the belt and the drum.

30 A second conduit in the form of the hollow casting 31 is mounted upon the pedestals 11. The side 32, of the casting 31, confronting the surface of the drum is curved upwardly concentric with the periphery of the drum and is formed with a plurality of elongated slots 33.

35 Air, or steam, is fed to the interior of the casting 31 through a supply pipe 34. With this arrangement, a sheet of compressed air is directed upwardly about the periphery of the drum, the surface 32 of the casting serving to direct the sheet upwardly and confine it against the periphery of the drum, whereby the leading end of the web is directed between the winder drum 17 and the winder roll 36.

40 When the web has been fed to the winder roll 36, the fluid is released from the cylinder 21, 45 permitting the arms 15 to swing downwardly

about the axis of the roll 14, moving the upper slack run 25 of the belt out of engagement with the web. This prevents any damage to the web during the winding operation.

The device described is adapted to be mounted under conventional web winders now in operation, and is effective to efficiently thread the web about the winder drum to the winder roll.

What I claim is:

1. A web threading device for drum winders comprising a frame, a pair of rolls journaled in the frame in parallel spaced relation and with the axes of said rolls extending parallel to the axis of the winder drum, an endless belt trained over said rolls, a support positioned intermediate said rolls for supporting the lower run of said belt and maintaining the upper run of the belt slack and out of engagement with the surface of the winder drum, power means operable to move at least one of said rolls toward the drum to bring a portion of the upper slack run of the belt into engagement with the periphery of the drum, said belt being driven by such engagement and operable to feed a web about the periphery of the drum, and means carried by the frame in juxtaposition to the discharge end of said belt and operable to discharge an air blast against the leading end of the web and maintain the same in engagement with the periphery of the drum.

2. A web threading device for drum winders comprising a frame, a pair of arms pivotally mounted at like ends to the frame and extending in juxtaposition to the under side of the winder drum, a pair of rolls journaled between the ends of said arms in parallel spaced relation, an endless belt trained over said rolls, a belt support carried by said arms and positioned intermediate said rolls and being cooperable to support the lower run of the belt and to maintain the upper run of the belt slack and normally out of engagement with the surface of the drum, means operable to move said arms about their pivot toward and from the drum and bring a portion of the upper slack run of the belt into engagement with the periphery of the drum, said belt being driven by such engagement and operable to feed a web about the periphery of the drum, means carried by the frame in juxtaposition to said pivot and operable to direct a blast of air against the leading edge of the web to force the same against the periphery of the drum.

3. A web threading device for drum winders comprising a frame, a pair of rolls journaled in the frame in parallel spaced relation and with the axis of said rolls extending parallel to the axis of the winder drum, an endless belt trained over said rolls, a support positioned intermediate said rolls for supporting the lower run of the

belt and maintaining the upper run of the belt slack and out of engagement with the surface of the winder drum, power means operable to move at least one of said rolls toward the drum to bring a portion of the upper slack run of the belt into engagement with the periphery of the drum, said belt being driven by such engagement and operable to feed a web about the periphery of the drum.

10 4. A web threading device for drum winders comprising a frame, a pair of rolls journaled in the frame in parallel spaced relation with the axis of said rolls extending parallel to the axis of the winder drum, an endless belt trained over said rolls and having an appreciable amount of slack, a support positioned intermediate said rolls for supporting the lower run of the belt substantially tangential to said rolls and maintaining the upper run of the belt slack and out of engagement with the surface of the winder drum, power means operable to move at least one of said rolls toward the drum to bring a portion of the upper slack run of the belt into engagement with the periphery of the drum, said belt being driven by such engagement and operable to feed a web about the periphery of the drum, a conduit mounted on the frame in juxtaposition to the discharge end of the upper run of the belt, said conduit being formed with an aperture directing a blast of gas against the leading end of the web to maintain the same in engagement with the periphery of the winder drum.

5. A web threading device for drum winders comprising a frame, a pair of rolls journaled in the frame in parallel spaced relation in juxtaposition to the lower portion of the winder drum, the axis of said rolls extending parallel to the axis of the winder drum, an endless belt trained over said rolls, means cooperable to maintain slack in the upper run of said belt and to maintain the same out of engagement with the periphery of the winder drum, power means operable to move said rolls toward the drum to bring a portion of the upper slack run of the belt into engagement with the under side of the drum, and said belt being driven by such engagement and operable to feed a web about the periphery of the drum, a conduit mounted on the frame in juxtaposition to the discharge end of the upper run of the belt and extending parallel with the periphery of the drum, the confronting surface of said conduit being curved and concentric with the periphery of the drum and being formed with a plurality of apertures arranged to direct a blast of air against the leading end of the web to maintain the same against the drum during the upward movement thereof.

CHARLES M. PEARSON.
